(57) **CLAIM**

The ornamental design for the screw on applicator, as shown and described.

DESCRIPTION

FIG. 1 is a nozzle side top perspective view of a screw on applicator;

FIG. 2 is a nozzle side plan elevation view of the screw on applicator;

FIG. 3 is a right side plan elevation view of the screw on applicator;

FIG. 4 is a top plan view of the screw on applicator;

FIG. 5 is a bottom plan view of the screw on applicator;

FIG. 6 is a blade side plan elevation view of the screw on applicator; and,

FIG. 7 is a blade side top perspective view of the screw on applicator.

Left side elevation view is mirror image of right side elevation view.

The broken lines depict portions of the screw on applicator in which the design is embodied that are not considered part of the claimed design.
